CONTROL DEVICE FOR A RECIPROCATING ELECTRIC FAN

Arthur K. Tateishi, Toronto, Ontario, Canada

Application September 21, 1956, Serial No. 611,142

6 Claims. (Cl. 230—259)

2

Fig. 8 is a view similar to Fig. 6, but showing speed regulating means for the louvers.

Fig. 9 is a sectional view taken on line 9—9 of Fig. 8.

Fig. 10 is a fragmentary view of Fig. 8 turned through 5 90°, and

Fig. 11 is a plan view of Fig. 8.

Referring now to the figures in detail, the exemplification of the fan according to the invention comprises a housing 1 forming a wind tunnel. The housing may be 10 made of a light gauge sheet metal, but is preferably made of plastic since the housing proper does not have to carry the weight of the fan mechanism. It is mounted on a base or standard 2 pivotal about a horizontal axis.

As seen in the direction of the air flow through the 15 housing, the fan mechanism comprises impeller blades 3, a fan motor 4 and a louver assembly 5.

The housing is composed of two generally ring shaped shells 6 and 7 which complement each other to form the housing. The two shells are closed by grill or wire 20 mesh guards 8 and 9 respectively which serve both, to prevent injury to persons or pets by the whirling fan blades and to protect the fan mechanism against damage. The wire mesh 9 at the front of the fan is preferably reinforced by crossing bars 10 and 11 which may support 25 a name plate 12. The inner wall of the housing is made cylindrical by either giving the inner peripheral wall of shells 6 and 7 a corresponding configuration, or by providing, as shown, a cylinder 13 made of thin metal gauge, or plastic material and fitted in the housing leaving spaces 30 13'. The interior of the fan constitutes a wind tunnel through which a straight flow of air relatively free of turbulence is forced by impeller blades 3.

Cylinder 13 also serves to anchor wire mesh 8 within shell 6. To this end, mesh 8 has an extension 8' held 35 between the cylinder and a corresponding wall portion of shell 6. The extension is bent to form a shoulder resting upon shell 6. Wire mesh 9 is anchored by resting with its rim upon shell 7. This reinforced rim is outwardly slanted to direct and confine the air flow deflected by the louver assembly as will be more fully explained hereinafter.

To obtain maximum efficiency, blades 3 are so mounted that they protrude with about two thirds of the blade area from rear shell 6. Wire mesh 8 also extends correspondingly beyond shell 6 to accommodate the protruding portion of blades 3.

To provide for wide angle air flow oscillation, the shell 7 is formed with its forward side edges recessed or concaved as at 110, as best shown in Fig. 2, which eliminates 50 interference of the housing with the air deflected at a substantial angle to the sides by the louver assembly 5.

The louver assembly comprises several identical louver slats or vanes made of thin sheet metal gauge or plastic, four louver slats 15 being shown. The slats are mounted 55 within shell 7 perpendicular to the fan axis and are arranged to have their forward portions project forwardly beyond the recessed sides 110 of the shell 7. To this end, flat metal or plastic strips 16 and 17 are secured by any suitable means on diametrically opposite sides of shell 60 7. These strips constitute mounting bases in which bearings for the louver slats are formed.

The slats are mounted to pivot about their longitudinal centre axis which at the centre of the slat is approximately in line with the recessed sides 110 of shell 7.

65 The width of the slats is such that the same do not overlap in any pivotal position, or in other words, such that slots for the passage of a straight air flow between adjacent slats remain in each pivotal position of the slats.

70 To obtain joint reciprocatory pivotal movement of the slats, the same are coupled by joining means more fully

This invention relates to electric fans of the blower type, more particularly to an electric fan producing an oscillating air flow.

It has been proposed to effect oscillation of the air flow by means of reciprocating louvers arranged directly in advance of air impeller blades, but the low efficiency and the serious problems of turbulence have prevented such fans from being commercially acceptable.

The main object of the invention as disclosed in my copending application Ser. No. 440,949 filed July 2, 1954 issued as Patent 2,768,782 is to provide a novel improved and greatly simplified electric fan which will efficiently produce a slowly oscillating air flow by means of reciprocating louvers without movement of the fan head with a minimum of turbulence and noise. The louvers of the fan are reciprocated by drive means which in turn are driven by the fan motor also rotating the impeller blades of the fan.

The fan of my copending application also comprises joint control means for controlling the circuit of the fan motor and actuating the drive means, the joint control means ensuring that the load of the louvers is not coupled to the fan motor until the motor has reached adequate speed. This affords the advantage that the louver reciprocation can be obtained with a smaller capacity motor than would be permissible if the louvers could be connected, even accidentally, to load the motor during the starting period which requires an increased starting torque.

The principal object of the present invention is to provide novel and improved regulating means for varying the rate of speed of the oscillations of the louvers without changing the R. P. M. of the motor.

Other and further objects, features and advantages of the invention will be pointed out hereinafter and set forth in the appended claims forming part of the application.

In the accompanying drawing several preferred embodiments of the invention are shown by way of illustration and not by way of limitation.

In the drawings:

Fig. 1 is an isometric front view of a fan according to the invention.

Fig. 2 is a side elevational view.

Fig. 2a is a rear elevational view of the fan.

Fig. 3 is a rear view with a rear part of the fan housing removed to show the fan mechanism.

Fig. 4 is a fragmentary sectional view of the control means of the drive means for the louver assembly of the fan and of the control means for the drive means and the fan motor.

Fig. 5 is a plan view of Fig. 4 partly in section.

Fig. 6 is a view of the components of Fig. 4 turned through 90° and showing the drive means and control means in one operational position.

Fig. 7 is a fragmentary view of Fig. 6 showing the drive means and the control means in another operational position.

described in the aforesaid copending application to form a louver assembly.

The fan motor is shown as a two-pole motor with a generally U-shaped field core 30. The plane base branch of such core permits conveniently to mount thereon the drive means and the control means of the fan. The drive shaft of the motor which protrudes from both sides of the rotor has its axis lying coincident with the axis of the cylinder 13, and intersecting the axis of the pivot of the fan housing 1 which pivots about the axes of fasteners 85. The protruding shaft end 31 of the motor shaft mounts blades 3 and is guided by a bearing formed in a plate 32 secured to the motor by any suitable means such as posts 33. The other shaft end of the motor serves to actuate the drive means and is preferably set off for this purpose at 31'. The motor and the components supported thereon are mounted in the fan housing by two laterally extending brackets. Each bracket is formed by two parallel bars 35 and 36 respectively which are secured to the motor by any suitable means such as the U-shaped portions 37. The bars may either be secured to the motor directly or to a plate fastened to the motor for this purpose. The free ends of bars 35 and 36 respectively are secured to a mounting plate 38 and 39 respectively.

The motor is connected with a suitable source of current by a connecting cord 105. To avoid an undue strain on this cord, the same is preferably meandered by means of guide pins 106, 107 and 108 extending from the inner wall of shell 7, as can best be seen in Fig. 3, thereby providing a strain relief for the connecting cord.

The drive means for the louver assembly and the control means of the fan

The drive means serve to transmit the rotation of the motor shaft to the louver assembly for imparting the required reciprocatory movements to the louver slats, and the control means serve to control the motor circuit and the drive means, independently one from the other.

The drive means comprise a shaft 40 on which is seated a large wheel 41 and a small wheel 42 to obtain the required ratio of transmission. Wheel 41 coacts with shaft end 31' by frictional engagement. To obtain a satisfactory power transmitting frictional engagement between wheel 31 and shaft 31' both, the wheel and the shaft end are preferably peripherally lined with a high friction material such as a rubber or a rubber composition. Shaft 40 is supported by an arm 43 pivoted at 44 to a right angle bracket 45. This bracket is secured to the motor as can best be seen in Figs. 4 and 6. The perpendicular part of the bracket (as shown in Figs. 4 and 6) is formed with a cut-out 46 to permit a free up and down movement of the end of arm 43 supporting shaft 40. As a result, wheel 41 constitutes a floater wheel which is in power transmitting frictional engagement with shaft end 31' only when pressed against the shaft end.

The small wheel 42 coacts with a horizontally mounted wheel 47 by frictionally engaging the peripheral rim of wheel 47 when the two wheels are moved toward each other. Wheel 47 is rotatably mounted on a rod 49 by any suitable means such as a bushing 48. Rod 49 has a threaded portion 49' which is screwed in a bracket 50 fixedly secured to the horizontal branch of bracket 45. As is apparent, rotation of rod 49 for instance, by means of a knurled or milled controlled knob 51 results in an axial up and down movement of rod 49 and hence of wheel 47. A loaded spring 52 abutting at one end against a shoulder of rod 49 or a washer 53 and at the other end against bushing 48 serves to bias wheel 47 into its lowermost position on rod 49 in which it is retained by a cotter pin 54.

Wheel 47 is coupled with the louver assembly by a bar or wire member 55 eccentrically secured at one end to wheel 47 and at its other end to the louver assembly.

Wire 55 may be secured to wheel 47 by any suitable means. There is shown a headed pin 56 upon which is fitted a closed loop formed at the respective end of wire 55.

5 Rotation of wheel 47 will impart a reciprocatory pivotal movement to all the louver slats. The arc performed by the louver slats can be conveniently set by appropriately selecting the eccentricity of headed pin 56, the length of wire 55 and the associated components relative 10 one to another. In practice, it has been found that pivotal movements of the slats through an arc of 45° will give satisfactory results.

15 The control means further comprise a switch 60 for controlling the motor circuit mounted on the horizontal branch of bracket 45. While this switch may be of any suitable type, a toggle switch as shown is preferred. The switch has a bifurcated actuating member 61 which coacts with an arm 62 extending from rod 49. This arm may be fixedly secured to the rod, or as shown be held 20 by two clamping nuts 63 and 64 to permit axial adjustment of the arm and to assure rotation thereof in unison with the rod.

The drive means and the control means just described, function as follows:

25 Let it be assumed that the drive means and the control means are in the positions shown in Figs. 4, 5 and 6. The switch 60 is then in its open position disconnecting the motor circuit. Wheel 42 is out of engagement with the wheel 47 and wheel 41 abuts against shaft end 31' only 30 with the pressure of its own weight. When knob 51 is now turned through a rather small angle in the direction of the arrow shown in Fig. 5, arm 62 snaps switch 60 onto its "on" position, thereby starting the motor which will turn blades 3 with its full force and speed. Although 35 rod 49 is slightly lowered by the intial rotation of knob 51, wheel 47 remains out of engagement with wheel 42. During this stage of the operation, wheel 41 may be rotated by shaft end 31', or may more or less slip relative thereto depending upon the friction between the 40 wheel and shaft end. In any event the engagement between the wheel and the shaft end is only slight and not capable of transmitting power. This affords the advantage that the wear and tear upon the peripheral surfaces of wheel 41 and shaft end 31' are negligible when the 45 blades only of the fan are operated.

It will be understood that while rod 49 is positively advanced by screw or cam action, the wheel 47 is free to travel axially of the rod and is biased under action of the spring 52 to engage the wheel 42 with the correct pressure for drive of the wheel 47 without requiring critical control of the movement of rod 49. Furthermore, this spring 52 will automatically compensate for any wear in rubber or metal parts.

This control arrangement ensures that the load constituted by the louvers and their driving disc 47 cannot even accidentally be imposed on the motor 4 when starting the motor. By eliminating any high starting torque a minimum capacity motor capable of delivering a given air flow may be employed, affording again a saving in cost 60 and weight. Further when the fan is shut off, the above arrangement ensures that pressure is automatically removed from all rubber surfaces thereby lengthening the life of rubber parts and eliminating deformation by set of the rubber parts.

65 When it is desired to start the louver assembly, rotation of knob 51 is continued until wheel 47 engages wheel 42 with a pressure sufficient to force the floating wheel 41 into power transmitting engagement with shaft end 31'. As a result, the rotation of the shaft end is transmitted 70 to wheel 47 which rotates about rod 49 and imparts through eccentric pin 56 and wire 55 the aforescribed pivotal movements to all the louver slats.

To stop first the louver assembly and then the fan blades, knob 51 is rotated in opposite direction. Such 75 opposite rotation of knob 51 first moves wheel 47 out

of engagement with wheel 42 and then switch 60 into its "off" position. As appears from the previous description, a single common control means permits selectively to operate either the fan blades only or the fan blades and the louver assembly jointly, operation of the fan blades only producing an air flow in a fixed direction and operation of the louver assembly an oscillation of the air flow by the effect of the reciprocating louver slats.

Standard of the fan

The standard comprises a base plate 70 from which extends two pairs of bent arms 71, 72 and 73, 74 respectively, the opposing pairs of arm portions 73 and 74 being spring urged inwardly to grip the housing 1 therebetween. These arms are joined at their free ends by caps 75 which form a base for fastening means enabling the shells of the housing and the components supported therein to be fastened by a single operation. The fastening means also serve as a horizontal axle about which the entire fan assembly may be tilted.

The drive means and the control means according to Figs. 4 through 7 correspond to those disclosed in the aforesaid patent 2,768,782. They impart to the louvers a fixed angle of reciprocation and have been included in this application to facilitate the understanding of the present invention. As stated before, the principal object of the present invention is to provide means for varying the reciprocatory speed of the louvers while maintaining constant the angle of reciprocation and the rotation speed of the motor.

As is apparent from the previous description, the movements of the louvers are controlled by the rotational speed of wheel 47 which in turn is controlled by the ratio of transmission between the shaft of the motor and wheel 47. The speed adjustment of Figs. 8 to 11 provides for a variation of this ratio by varying the radial distance at which drive wheel 42 engages driven wheel 47.

To this end wheel 41 is secured to a sleeve 125 to which is also secured drive wheel 42. Sleeve 125 is axially slidable on a shaft 40'. To permit an axial displacement of the sleeve and with it of wheel 41, the shouldered part 31" of the motor shaft is correspondingly extended. As is apparent, axial displacement of sleeve 125 will correspondingly vary the rotational speed of driven wheel 47 for a given constant rotational speed of the motor.

To effect axial displacement of the sleeve, a grooved collar 126 is secured to the sleeve and engaged by an actuating means generally designated by 127.

The actuating means is shown as comprising a member of generally U-shaped configuration. The member is rotatably seated with its branches 128 and 129 on rod 49 and bracket 50 respectively so that it can participate in the slight up and down movement of rod 49 when the latter is rotated for controlling the motor drive as previously described. To provide the necessary space, bracket 45 of Figs. 4 through 7 has been modified to comprise a part 45' similar to the previously described bracket, for mounting shaft 40' and a raised horizontal tongue 45" mounting switch 60. The lower horizontal bracket 129 of the U-member extends between the horizontal part of bracket 45' and tongue 45" as can best be seen in Fig. 8. This figure also shows that the rotation of switch rod 62 and the actuating means 127 do not interfere one with the other.

Rotation of the U-shaped member is transmitted to collar 126 by means of a toothed section 130 on branch 129 and a rack 131 from which extends a slanted arm 132 ending in a bifurcated portion 132' straddling collar 126. Rack 131 is slidable on bracket part 45' parallel to the rotational axis of wheel 41 and is provided for this purpose with two elongated slots 131' engaged by pins 133.

Rotation of the U-shaped member about the axis of rod 49 effects axial displacement of sleeve 125 and the parts associated therewith in one direction or the other. To facilitate setting of the adjustment means, an arm

134 ending in a finger grip 135 extends from the upper bracket 128 of the U-shaped member. This arm is situated outside of housing 1, preferably adjacent to knob 51. Fig. 11 indicates the required angular movement 5 for causing faster or slower oscillations or reciprocations of the louvers.

To prevent rattling of the assembly and to detain the speed adjustment at definite settings, detents 136 are preferably provided on rack 131. These detents coast 10 with a soft spring 137.

As is evident from the previous description, the illustrated speed adjustment means can be altered in various respects without departing from the scope of the invention.

15 What is claimed is:

1. A control device for controlling the operation of an electric fan of the kind including impeller blades rotatably mounted on the intake side of the wind tunnel for producing an airflow therethrough, a louver assembly including several parallel louver slats disposed at the delivery side of the tunnel, motor means drivingly connected with said blades for rotating the same; driving means for drivingly connecting said motor means with said louver assembly to impart to the slats thereof a reciprocatory movement through a predetermined constant angle, said drive means including an input wheel frictionally engageable with the drive shaft of said motor means, an intermediate wheel mounted for rotation in unison with the input wheel, an output wheel frictionally engageable with said intermediate wheel, coupling means connecting said output wheel with said louver means for imparting said reciprocatory movement to the louver slats upon rotation of said output wheel, and control means for moving the said wheels into and out of rotation transmitting frictional engagement with each other and said motor drive shaft for coupling the motor means with the louver means, said control means comprising a regulating means included in said drive means, said regulating means including means for axially displacing said intermediate wheel to vary the radial distance between the point of engagement of the intermediate wheel with the output wheel and the rotational axis of the output wheel for regulating the ratio of transmission between the rotational speed of the motor means and the speed of the reciprocatory movement of the louver assembly, thereby regulating the rate of speed of the reciprocatory movements of the louver slats while maintaining constant the rotational speed of the motor means and the angle of the slat movements.

2. A control device according to claim 1, wherein said input wheel and said intermediate wheel are seated on a common shaft which is supported displaceable parallel to the drive shaft of the motor means, and said output wheel is seated on a shaft disposed perpendicular of the aforesaid shafts and axially displaceable by said control means whereby displacement of the output wheel shaft in the respective direction moves the output wheel into frictional pressure engagement with the intermediate wheel and the input wheel into frictional pressure engagement with the motor drive shaft, said intermediate wheel being axially displaceable on said common shaft to vary said point of engagement.

3. A control device according to claim 2, wherein a sleeve axially slidable on said common shaft mounts said intermediate wheel, and wherein a linkage means is operatively connected with said sleeve for axially displacing the same, said linkage means including an actuating member protruding from said wind tunnel for actuating the regulating means from the outside of the wind tunnel.

4. A control device according to claim 3, wherein said linkage means include a rack and toothed sector link for converting a rotary movement of the actuating member into the linear movement of the sleeve.

5. A control device according to claim 4, wherein said linkage means further include a link pivotal about the shaft of the output wheel, said pivotal link mounting said toothed sector and said actuating member.

6. A control device according to claim 5, wherein said linkage means also include detent means for yieldably arresting said actuating member in a selected one of several predetermined positions.
